UNITED STATES PATENT OFFICE.

EDWARD CRAIG, OF ST. JOSEPH, MICHIGAN, ASSIGNOR TO SARANAC AUTOMATIC MACHINE CORPORATION, OF BENTON HARBOR, MICHIGAN, A CORPORATION OF DELAWARE.

METHOD OF MAKING WIREBOUND-BOX BLANKS.

Application filed June 28, 1924. Serial No. 723,052.

To all whom it may concern:

Be it known that I, EDWARD CRAIG, a citizen of the United States, and resident of St. Joseph, Berrien County, Michigan, have invented a certain new and useful Improvement in Methods of Making Wirebound-Box Blanks, of which the following is a specification.

This invention relates to the manufacture of wire-bound box blanks for the production of wire-bound boxes of that kind in which the sides or sections or sheets of the blank are reinforced, or some of them, by means of cleats secured thereto, and are flexibly connected together by parallel binding wires which are stapled to the sheets and the cleats, so that each blank is foldable into box form.

More particularly, the invention relates to the manufacture of wire-bound box blanks by machinery of that kind in which means are provided for propelling or feeding cleats along with the other materials, for one or more of the sheets of each blank, so that each blank will have one or more cleated sections, as well as one or more cleatless sections. In the use of machinery of this kind, the sheets and cleats are delivered in any suitable manner to the work feeding means for feeding the sheets and cleats forward below the staplers, and for this purpose endless belts or sprocket chains are usually employed, and guides are provided for the cleats. The said belts or sprocket chains, however, are ordinarily provided with sheet spacers, or projections which extend between the sheets, to properly space the sections of blanks apart, and said belts or chains are also provided with cleat pushers for engaging and propelling the cleats along the guides, whereby the staples which are driven by the stapling mechanism to secure the binding wires in place serve also to attach the cleats to their respective sheets or sections of the blank. Ordinarily, the staples which are employed for securing the wires to sheets having cleats are longer than the staples which are driven to secure the wires to the cleatless sheets. In this way each blank is provided with one or more cleated sheets, and with one or more cleatless sheets, depending on the number of cleat pushers employed on

said belts or sprocket chains to feed the cleats.

Generally stated, the object of the invention is to provide an improved process or method whereby machinery of the foregoing general character may be employed for the manufacture of wire-bound box blanks having cleats on each and every sheet or section thereof, or having cleats on more sections thereof than is called for by the number of cleat pushers on the feed belts or sprocket chains, so that either a partially cleated blank or a full-cleated blank, for example, may be made on one and the same machine, without changing the number of cleat pushers thereon, and practically without making any alteration in the machine itself.

It is also an object to provide certain details and novel method features and combinations of steps tending to increase the general efficiency and the desirability of a wire-bound blank method or process of this particular character.

It is also an object to obviate the necessity of using certain things heretofore considered necessary in the production of wire-bound boxes.

To the foregoing and other useful ends, the invention consists in the matters hereinafter set forth and claimed, and shown in the accompanying drawings, in which—

Fig. 1 is a longitudinal, vertical section of a wire-bound box blank machine of the general character previously mentioned, with one end of the machine shown broken away for convenience of illustration.

Fig. 2 is a plan of certain portions of said machine.

Fig. 3 is a perspective of one form of blank to be made on said machine.

Fig. 4 is a perspective of a different form of blank to be made on said machine.

Fig. 5 is a perspective of one of the previously cleated sheets or sections employed in the manufacture of blanks in accordance with the invention.

Fig. 6 is a perspective of one of the cleatless sheets or sections employed in the manufacture of blanks on said machine.

Fig. 7 is a perspective of one of the cleats employed in the manufacture of blanks by the improved method or process.

As thus illustrated, the machine shown comprises a body frame 1 having parallel and longitudinally extending guides 2 for the cleats of the blanks. Parallel sprocket 5 chains or feed belts 3 are employed, in the usual manner, these being mounted on sprockets 4 at each end of the machine. The said belts are provided with cleat pushers 5 which extend into the guides 2 to push 10 the cleats along therein. It will be understood that these feed belts or sprocket chains are operated intermittently, in any suitable or desired manner, so that the materials are fed intermittently below the 15 stapling mechanism 6, which latter can be of any suitable or desired form also. Anvils 7 are arranged to enter the guides 2, automatically, being pivoted at 8 and controlled by springs 9, so that these anvils 20 will support any cleatless sections of the blanks to clinch the staples on the under surface thereof. Wire 10 is supplied to the stapling mechanism for the production of the staples, and the machine thus shown 25 and described is of a common and well known form, being equipped with four cleat pushers 5 for each and every blank, so that the blanks to be made in the ordinary manner will be of the character shown in 30 Fig. 3 of the drawings. Such a blank comprises the four sections 11, 12, 13 and 14, the sections 12 and 14 having cleats 15, but the sections 11 and 13 being left cleatless, whereby the blank is of a well known form 35 commonly called an alternate-cleat blank. The binding wires 16 are secured to the blank by the staples 17 and 18, the staples 17 being longer than the staples 18, whereby the staples 17 secure the cleats 15 to the 40 sections 12 and 14. The cleat pushers 5 of the machine are disposed in position to engage the cleats 15, and in addition said machine is provided with sheet spacers 19 for the separation of the sheets, so that spaces 45 will be provided between the edges of the sheets or sections of the blank, thereby to insure correct folding of the blank, when the same is folded into box form. Any cleatless sheets are necessarily supported on 50 the blocks which have the sheet spacers 19 and cleat pushers 5, as shown, these blocks being secured at predetermined intervals to the belts 3, so that underneath support is necessary for only the unattached cleats, 55 before the cleats reach the staplers. But of course, during the stapling operation the cleats must be supported.

Now for the production of the blank shown in Fig. 4, the same machinery is 60 employed, but in this case the sections 20 and 21 are provided with cleats 22, which are partially secured thereto by staples 23 driven by an ordinary cleating machine. Thus the sections 20 and 21 come to the 65 machine already equipped with cleats, and

consequently the machine does not require any cleat pushers for the cleats 22, inasmuch as these cleats are carried by their respective sheets, and are automatically fed or propelled along the guides 2 in the 70 desired manner. Thus for the production of a blank of the kind shown in Fig. 4, which is a full-cleated or eight-cleated blank, the operator or attendant will place loose cleats in position against the cleat pushers 75 5, and will place sheets thereon, and will then place the two cleated sections 20 and 21 in position. The materials will then go forward below the stapling mechanism, and will have the binding wires 16 secured 80 thereto in the usual manner. The sections 20 and 21 will have more staples than the other sections, inasmuch as the staples 23 are provided in addition to those driven by the box-blank machine itself. 85

It will be seen that the cleats are preferably of the tongue and groove kind, being tongued and grooved at their ends to fit together nicely when the blank is folded into box form. Thus either form of blank 90 can be made on one and the same machine. It is obvious, of course, that another form of blank can be made by supplying only one previously cleated sheet, so that the blank 95 will have three cleated sheets and one un-cleated sheet when finished. In any event however, the invention contemplates a method of manufacturing box blanks whereby the number of cleats on the blanks can be increased or varied without changing 100 the number of the cleat pushers on the feed belts or sprocket chains by which the materials are fed or moved along to receive the staples from the stapling mechanism. The wires, of course, are secured progressively to the blank, and are 105 cut off at their ends in a manner to provide wire ends which can be twisted together to close the box when the blank is folded into 110 box form. It is obvious, of course, that 115 any kind of heads or end walls (not shown) can be employed to close the ends of the box, and it is obvious that these heads or end-walls can be secured to the cleats, or some of them, in the usual and well known 120 manner.

As thus shown, the chains or belts 3 travel in the direction indicated by the arrows in Figs. 1 and 2, and the cleats which slide in the guides 2 will push the anvils or clinch 125 blocks 7 out of the way, so that these anvils will only move into operative position when cleatless sheets come along. When blanks of the kind shown in Fig. 3 are produced, the anvils 7 will move under the sections 11 and 13, to clinch the staples 18, and will be pushed automatically out of the way by the cleats of the other sections. Thus the machine may have any suitable or desired 130 number of cleat pushers 5 and is not limited

to any particular number, for by means of the method or process shown and described different kinds of blanks can be made on the machine without changing the number of 5 cleat pushers thereon. The invention contemplates, therefore, the feeding of loose cleats for one or more sheets of each blank, and the feeding of previously fastened cleats for one or more sheets of each blank, so that 10 the production of each blank involves the use of cleats which must be initially fastened in place by the same staples by which the wires are secured in place, and the use of other cleats which are fastened in place 15 to the sheet material before entering the machine. Thus for any previously cleated sheet or sheets, no cleat pushers are necessary, and the cleat-pusher method co-operates with the pre-cleating method (or cleat pusherless method) to produce a blank having more cleats than are called for by the number of cleat pushers on the machine, or more 20 than would be possible to fasten in place by the box-blank machine itself. As shown, 25 the box-blank machine is operative to fasten cleats on two sections of the blank; but if another section is to be cleated, or if all the sections are to be cleated, it is obvious 30 that the blank machine itself is inoperative 35 to do that, and hence the additional cleats must come to the machine already attached to their respective sheets, if blanks having more than two cleated sections are to be made without changing the structure of the 40 machine. Thus, as stated, the pre-cleating method is combined with and employed to co-operate with the cleat-pusher method to produce blanks having more cleats than can be fastened in place by the blank machine 45 itself, and different kinds of blanks can be made, depending upon circumstances and requirements and the use to be made of the boxes. All of the sheets, whether cleated or 50 uncleated, are spaced apart and carried on the blocks of the chains or feed belts, so that each sheet is individually propelled by pressure exerted at its rear edge, and there is no crowding together of the sheets and no 55 communication of feeding or propelling motion from one sheet to another. Consequently, the back pull exerted by the binding wires, as the blanks move along below the stapling mechanism, is communicated successively to the different sheets, and from each sheet directly to the feed belts, so that 60 compression of the sheets together is avoided, and at the same time the blank machine will serve to staple both unattached and previously attached cleats to their respective 65 sheets. The pre-cleating of sheets can be done by an ordinary cleating machine, or in any suitable manner, and when a full-cleated blank is desired, such as the one shown, the materials will be supplied accordingly, so that some sheets are uncleated

and some sheets are cleated, and the cleated sheets will alternate with the uncleated sheets on the machine, with loose unattached cleats below each cleatless sheet, before the cleats are all secured in place by the staples 70 which are driven crosswise of the binding wires to secure the wires to the sheets and cleats to form blanks which can be folded into box form.

Thus a partially cleated blank having one 75 or more cleatless sections can be made on a machine designed for that purpose, and by using previously attached cleats and unattached cleats, as explained, a full cleated blank, or at least one having more cleats 80 than is contemplated by the feeding apparatus, can be made on a machine designed primarily for the making of a blank having one or more cleatless sections. Thus the method contemplates the use of loose cleats 85 and previously attached cleats in the wiring of one and the same blank.

Thus it will be seen that in the practice of the method shown and described, whereby either a cleated or a partially cleated blank may be made on one and the same machine, no spacer blocks are necessary between the cleats, as the pusher system is employed instead, even when pre-cleating is used for one or more of the sheets. 90 The pushers 5 push any loose cleats which are placed in the stationary guides, so that any misplacement or disarrangement of the cleats is unavoidable and automatically rectified, as the loose cleats cannot move forward under the staplers, of course, except as the pushers 5 are in firm engagement with the rear ends of such cleats; but any previously attached cleats, for precleated sheets, 95 are not capable of any misplacement or disarrangement in the blank machine, as they are properly placed on the sheets before entering the machine, and the precleated sheets push and carry their allotted cleats forward in the stationary guides, so that the pusher system is employed for the cleats in the making of either type of blank. Of course, the spacer system is employed for the sheets, as spacers 19 are interposed between the cleats for precleated sheets. 100 These sheet spacers have three functions, first to space the sheets, second to propel the sheets forward, against any drag or back pull of the binding wires, and third to propel the cleats of any precleated sheets. Thus the cleats do not ride on a moving structure of any kind, but to the contrary are pushed and caused to slide in stationary guides so that misplacement or disarrangement of any 105 loose cleats is necessarily automatically rectified as the result of retardation of the cleats by the guides or other elements with which they come in contact, or by which they are opposed, ensuring firm contact of 110 the rear ends of such cleats with their al-

lotted pushers while passing under the staplers, and thus ensuring automatic rectification of any misplacement or disarrangement of loose cleats, and obviating the necessity of using spacers between the cleats to initially position the cleats before placing them in the blank stapling and wiring machine. Frictional retardation, therefore, is employed to automatically rectify any misplacement or disarrangement of loose cleats, relatively to previously attached cleats, thus obviating the use of the spacer blocks between any of the cleats.

What I claim as my invention is:

- 15 1. A method of making wire-bound box blanks by securing sheets and cleats and binding wires together by machinery, comprising the feeding of loose or unattached cleats under one or more sheets of each blank, and the feeding of previously attached cleats under one or more sheets of each blank, thereby causing the sheet material to initially position some cleats in each blank, while requiring individual positioning of other cleats, so that for each blank there are some previously attached cleats which are carried along by the sheet material, and also some unattached cleats to be secured to one or more sheets by the machinery for making the blanks, maintaining the sheets and cleats in relative position while moving along, inserting staples to secure binding wires in place to flexibly connect the sections of the blank together and 30 to secure both the attached and the unattached cleats to their respective sheets, so that some cleats are propelled by individual pressure on their rear ends, while other cleats are necessarily propelled by 35 the sheet material.
2. A method as specified in claim 1, in which cleat pushers form the means for maintaining the unattached cleats in relative position.
- 45 3. A method as specified in claim 1, in which the means for maintaining the sheets in position prevent the sheets from jamming together at their edges and form the means by which propelling motion is individually communicated to each sheet at the 50 rear edge thereof, so that the back pull of the binding wires is sustained by each sheet individually, regardless of whether such back pull is being exerted on a previously 55 cleated sheet or a sheet to which the cleats are being initially attached by the stapling of the binding wires thereto.
- 60 4. In the manufacture of wire bound box blanks by machinery having both sheet feeding means and cleat feeding means, a method of making blanks having more cleats than said cleat feeding means is operative to feed, comprising the placing of one or more previously cleated sheets in 65 position for the blank, so that some cleats

are attached prior to the wiring operation, placing some unattached cleats in position relatively to the previously attached cleats, placing one or more sheets on unattached cleats, the sheet feeding means spacing the 70 sheets apart, exerting pressure on the rear edges of the sheets, causing the precleated sheet or sheets to propel the cleats thereof, exerting pressure against the rear ends of unattached cleats to propel them in unison 75 with the sheets and other cleats, and stapling binding wires to the sheets and cleats to flexibly connect together the different sections of the blank.

5. In the manufacture of wire-bound box 80 blanks by machinery having both sheet feeding means and cleat feeding means, a method of making blanks having more cleats than said cleat feeding means is operative to feed, comprising the placing of 85 one or more previously cleated sheets in position for the blank, so that some cleats are attached prior to the wiring operation, placing one or more cleatless sheets in proper 90 position for the blank, placing unattached cleats in position to be attached to said cleatless sheets, the sheet feeding means spacing the sheets apart, exerting pressure on the rear edges of the precleated sheets to cause the same to propel the cleats thereof, 95 exerting pressure against said cleatless sheets and said unattached cleats to propel them in unison with the precleated sheets, and stapling binding wires to the sheets and cleats to flexibly connect together the 100 different sections of the blank.

6. The improved method of manufacture of wire-bound box blanks comprising placing in position one or more precleated sheets, placing in position one or more unattached cleats, placing a sheet or sheets in position over said unattached cleats, exerting feeding pressure on the rear of said unattached cleats and at the rear of said sheets, whereby the assembly material is 105 fed forward and the use of spacer blocks between the cleats and the exertion of back pressure on the front ends of the cleats are obviated.

7. A method of making wire bound box 115 blanks by securing cleats and binding wires together by machinery, comprising the feeding of loose or unattached cleats under one or more sheets of each blank and the feeding of previously cleated sheets for the other sheets of each blank, so that for each blank there are some previously attached cleats which are carried along by the sheet material and also some unattached cleats which are to be secured to their sheets, spacing 120 and maintaining said sheets apart during the feeding thereof to prevent jamming of their edges together, propelling each sheet individually by pressure communicated thereto at the rear edge thereof, so that the 130

back pull of the binding wires is sustained bound box blanks, comprising the assembly each sheet individually, regardless of having cleats therebeneath, individually pro-
whether such back pull is being exerted on a previously cleated sheet or on a sheet ini-
tially to be attached to the cleats by the binding wires, and applying binding wires to the
binding wires, and applying binding wires sheets and cleats as they are so propelled.
to the cleats and sheets as they are fed.

8. The improved method of making wire

EDWARD CRAIG.
